UNITED STATES PATENT OFFICE.

MARCIENE J. ORTH, OF LORAIN, OHIO.

COMBINED HIGH CHAIR AND CRADLE.

1,366,274.

Specification of Letters Patent. Patented Jan. 18, 1921.

Application filed August 27, 1920. Serial No. 406,419.

To all whom it may concern:

Be it known that I, MARCIENE J. ORTH, a citizen of the United States, residing at Lorain, in the county of Lorain, State of Ohio, have invented certain new and useful Improvements in Combined High Chairs and Cradles; and I do hereby declare the following to be a full, clear, and exact description of the invention, such as will enable others skilled in the art to which it appertains to make and use the same.

This invention relates to improvements in chairs and particularly to convertible chairs.

15 One object of the invention is to provide a child's high chair the legs of which are formed and mounted in a novel manner to permit of easy and quick raising and lowering to adjust the chair to different heights.

20 Another object is to provide a chair of this character that is capable of being easily and quickly converted into a small bed or crib.

25 Other objects and advantages will be apparent from the following description when taken in connection with the accompanying drawing.

In the drawing:

Figure 1 is a side elevation of a chair made in accordance with my invention in condition for use as a chair.

Fig. 2 is a front elevation of the same.

Fig. 3 is a side elevation of the chair converted into a crib.

35 Fig. 4 is an enlarged, sectional, detail view through the intersecting portions of two of the legs of the chair on the line 4-4 of Fig. 1.

40 Referring particularly to the accompanying drawing, 10 represents a pair of parallel horizontal members having their opposite ends turned downwardly at 12 and fitted with floor engaging casters. Connected to the forward end of each of the 45 members 10 by means of a hinge 14 is an upwardly inclined tube 15, while a similar tube 16 is connected to the other end of each of the members 10 by a hinge 17. The upper end of the pairs of members 15 and 50 16 are disposed in crossed relation, and sliding on the outer face of each of the members 15 is an offset plate 18 having its free end slidably engaged in a groove 20 formed longitudinally in the lower face of the member 16. By this construction the tubular members 15 and 16 are capable of pivotal

movement on their hinges 14 and 17, respectively, so that their upper ends slide past each other in crossed relation. Telescoped into the upper end of each of the 60 members 15 and 16 is a rod 21, the upper ends of said rods being connected to the seat bottom 22 by means of the hinges 23. The other end of each of the plates 18 is secured to one of the rods 21 by means of a 65 bolt 18' which slides in a longitudinal slot 15' or 16' formed in the members 15 and 16. Pivotedly secured to each rear corner of the seat bottom 22 is a downwardly extending link 24 which is pivotally connected at 70. 25 to a similar link 26 which is pivotally and slidably connected to the rear end of the member 10. Pivotally connected to the rear edge of the seat bottom 22 is the back member 27 of the chair, and formed on the upper end of said back member is a rearwardly and downwardly turned portion 28, the purpose of which will appear hereinafter. Carried by the forward edge of the seat bottom is a depending foot rest 29. Suitable 80 arms 30 are secured to the side edges of the seat bottom. By this construction the tubular members 15 and 16 are capable of pivotal movement on their hinges 14 and 17, respectively, so that their upper ends slide 85 past each other in crossed relation.

The link 24 is slotted at 25' to receive a clamping bolt and nut 26' disposed through the upper end of the link 26. Thus the links can be held in rigid, vertical alinement to 90 hold the seat and base members 10 in proper spaced relation.

When it is desired to adjust the height of the chair the nut and bolt 26' are loosened and the seat bottom 22 moved upwardly or 95 downwardly, according to the height desired, which will result in the rods 21 sliding out of or into the tubular members 15 and 16. The members 19 and 31 will guide the members 15 and 16 in their pivotal movement. When the chair has been adjusted to the height desired, the nut of the bolt 26' is tightened. Carried by the rear ends of the arms 30 are the transversely extending spring pressed bolts 32 which engage in 100 105 openings 33 in the sides of the chair back 27 to hold the back in upright position.

When it is desired to convert the chair into a crib, the bolts 32 are withdrawn from the openings 33 and the back let down until 110 the portion 28 rests on the floor. Prior to this adjustment of the back the joint 25 is

loosened and said joint swung inwardly toward the members 16 and 21 and the seat bottom 22 pushed downwardly so that the seat bottom will be in horizontal alinement 5 with the back which has been swung downwardly. The seat bottom and the back member thus form a continuous bed surface.

Slidably disposed through each arm 30, and arranged to be pulled outwardly from 10 the rear thereof, is a rod 34, the outer end of which is turned angularly, as at 34', for engagement in a socket 35, in the back, when the device is in lowered position, for use as a crib, as clearly seen in Fig. 3.

15 What is claimed is:

A convertible high chair comprising a base having crossed tubular members mov-

ably connected thereto, a seat bottom having rods movably connected thereto and slidably engaged in the tubular members, a back 20 member movably connected with the seat bottom and arranged to be swung into horizontal position, and a brace member between the base and seat bottom arranged to be moved inwardly to permit the seat bottom 25 being lowered into the plane of the back member.

In testimony whereof, I affix my signature in the presence of two witnesses.

MARCIENE J. ORTH.
